(57) **CLAIM**

The ornamental design for a support arm, as shown and described.

DESCRIPTION

FIG. 1 is a front perspective view of the support arm embodying the new design;

FIG. 2 is a rear perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines immediately adjacent to the shaded areas represents the bounds of the claimed design while all other broken lines depict portions of the support arm that form no part of the claimed design.
